UNITED STATES PATENT OFFICE.

SCOTT ARMES, OF MONTGOMERY, INDIANA.

WIRE-STRETCHER.

No. 809,767.

Specification of Letters Patent.

Patented Jan. 9, 1906.

Application filed May 31, 1905. Serial No. 263,088.

To all whom it may concern:

Be it known that I, SCOTT ARMES, a citizen of the United States, residing at Montgomery, in the county of Daviess, State of Indiana, have invented certain new and useful Improvements in Wire-Stretchers; and I do hereby declare the following to be a full, clear, and exact description of the invention, such as will enable others skilled in the art to 10 which it appertains to make and use the same.

This invention relates to wire-stretchers, and has for its object to provide a device of this nature especially adapted for stretching 15 woven-wire fence, which will be extremely simple, easy of operation, and cheap of manufacture.

Other objects and advantages will be apparent from the following description, and it 20 will be understood that changes in the specific construction shown and described may be made within the scope of the claim and that any suitable materials may be used without departing from the spirit of the invention.

In the drawings forming a portion of this specification, and in which like numerals of reference indicate similar parts in the several views, Figure 1 is a side elevation of the 30 present stretcher in use. Fig. 2 is a longitudinal section through the wire-engaging boards, taken on line 2 2 of Fig. 1. Fig. 3 is a section through the face-plate.

Referring now to the drawings, the present invention comprises a face-plate 5, having an opening 6 therein in which there is slidably engaged for longitudinal movement a threaded rod 7, formed of suitable metal, which is bifurcated at one end, the resulting 40 spaced portions being turned outwardly and rearwardly to form hooks 8, with which are engaged the rearward ends of chains 9.

A pair of wire-engaging plates 10 are provided, having vertically-arranged series of 45 perforations 11 therein, and these plates are disposed parallel to each other, the openings 11 registering for the reception of attaching-bolts 12. With the uppermost and lowermost of these bolts 12 there are engaged the 50 spaced legs 14 of yokes 15, having eyes 16, in which hooks 17, carried by the forward ends of the chains 9, are engaged. The legs 14 are engaged with the bolts 12 exteriorly of

the plates 10, as shown. A recess 18 is formed in the rearward face of the face-plate 5 and surrounds the opening 6 for the reception of a washer 19, which is engaged with the rod 7 and which receives thereagainst the inner end of an interiorly-threaded sleeve 20, which is engaged with the rod 7 and which 60 has a crank 21 formed integral therewith by means of which it may be rotated.

In use the attaching-bolts 12 are disengaged to permit of separation of the plates 10, after which these plates are disposed 65 against the opposite sides of a piece of wire fabric 22, which is to be stretched. The hooks 17 having been engaged in the eyes 16 and the yokes having been engaged with their bolts 12, the chains 9 are engaged with 70 the hooks 8 and the rod 7 is passed through an opening 23 in a supporting-post 24, the face-plate 5 being then engaged with the rod at the opposite side of the post from the plates 10. The sleeve 20 is afterward engaged with 75 the rod and may be rotated, as will be readily understood, to draw the rod through the post and face-plate to stretch the fence.

What is claimed is—

As an article of manufacture a wire- 80 stretcher comprising a face-plate having an opening therethrough, said opening being enlarged at one end, a washer disposed in said enlargement, a threaded rod slidably and removably engaged in the opening and 85 washer, a threaded sleeve removably engaged with the rod and bearing against the washer, a rotating crank formed integral with the sleeve, said rod being bifurcated at one end and having its resultant spaced portions turned outwardly and in the direction of the other end of the rod to form hooks, chains removably engaged with the hooks, hooks carried by the chains, wire-engaging plates adapted for the reception of fencing 95 therebetween, attaching-bolts engaged in the plates, and yokes removably engaged with certain of said bolts, the second-named hooks being engaged with the yokes.

In testimony whereof I affix my signature 100 in presence of two witnesses.

SCOTT ARMES.
